(57) **CLAIM**

The ornamental design for a product tray, as shown and described.

DESCRIPTION

FIG. 1 shows a right front perspective view of a product tray of the present design;

FIG. 2 is a left rear perspective view thereof;

FIG. 3 is a top-down view thereof;

FIG. 4 is an upward view thereof;

FIG. 5 is a side view thereof;

FIG. 6 is a front view thereof; and,

FIG. 7 is a rear view thereof.

The solid lines in FIGS. 1-7 illustrate a product tray according to the present invention.

1 Claim, 4 Drawing Sheets
